UNITED STATES PATENT OFFICE.

ANDREAS LURZ, OF VIENNA, AUSTRIA-HUNGARY, ASSIGNOR OF ONE-HALF
TO HUGO RITTER GABLER VON ADLERSFELD, OF VIENNA, AUSTRIA-
HUNGARY.

METHOD OF PRODUCING PLATINA COPY-PAPER.

SPECIFICATION forming part of Letters Patent No. 758,086, dated April 26, 1904.

Application filed November 19, 1901. Serial No. 82,846. (No specimens.)

To all whom it may concern:

Be it known that I, ANDREAS LURZ, photographer, a citizen of Austria, residing at VIII Josefstadtterstrasse No 33, at Vienna, Province 5 of Lower Austria, Austria-Hungary, have invented certain new and useful Improvements in Methods of Producing Platina Copy-Paper; and I hereby declare the following to be a full, clear, and exact description of the invention, such as will enable others skilled in the art to which it appertains to make and use the same.

The usual photographical platina method essentially consists in the use of a sensitive substance of suitable platina salts, which is spread on the paper to be prepared. The first trials to obtain platina-photographs have been based on the use of a salt requiring the development of the image by means of a hot solution; 15 but such images have a characteristic sepia color. Until now the papers have been prepared by spreading the suitable salt solutions on one side of the paper. The results of this method depend on the skill of the operator. On the one hand, these methods of spreading require a greater quantity of liquid. On the other hand, bubbles are formed in accordance with the nature of the solutions. The removal of these bubbles consumes con- 20 siderable time, and the surface of the paper is softened, and the substance penetrates too deep in the paper in consequence of its specific weight, while the points of the fibers rest dry and the paper and also the copies ob- 25 tained with the same receive a "weak" color. It is also to be noted that the substances are highly hygroscopic and that they are thinly liquid, causing crystallizations of the substances during the operation under the weak- 30 est draft of air or when the temperature is not favorable, while also the crystals absorb the moisture of the air and are dissolved. In both cases the paper is worthless. The practice has shown that it is not possible to mix 35 the sensitive layer of the solutions before spreading it; but it is necessary to bring the various salt solutions separately on the paper in such a manner that the following solution

is spread after the drying of the preceding layer. Also it must be observed that the 50 spreading of every salt solution must be made in one operation in order to avoid an unequally prepared paper.

The purpose of the present invention is to avoid the disadvantages before mentioned; and 55 the method consists, essentially, in covering the surface of the paper to be prepared with the suitable salt solutions in a certain succession, while every following layer is only spread after a complete drying of the preceding 60 layer. The several layers are not spread at once, but in three operations. The paper is first prepared, then the substance spread and carefully distributed over the whole surface of the paper, while the spreading is made im- 65 mediately after the first moistening. The substances are applied to the paper by means of three rollers or cylinders, each dipping in a trough containing the solution. The end cylinders are smooth-rubber cylinders, and the 70 middle one is a felt cylinder. One of the rubber cylinders serves for the preliminary preparation (the moistening) of the paper, the felt cylinder serves to spread the substance, and the third rubber cylinder distributes 75 equally the substance. The substance is spread directly on the moistened paper, and the distribution is effected immediately after spreading by means of a cylinder which dips in the substance. Every such layer is formed by 80 three operations. There are as many spreading devices as solutions of different composition, and between each two of these spreading devices a drying apparatus is inserted for the purpose of drying the first spread sub- 85 stance before the next follows.

Preferably, the operation is made in such a manner that the paper is led over the cylinders, dipping in the trough without counter-pressure, so that only the under surface of 90 the paper will be prepared. This has the advantage that the specifically heavier particles of the solutions rest more on the fiber-points and penetrate less in the paper, so that a completely smooth surface can be obtained.

In the accompanying drawing there is shown

diagrammatically a form of an apparatus for carrying out the operation.

- Each of the spreading devices A B consists of three rollers or cylinders *b c d*, dipping in 5 a common or in a separate trough *a*. The cylinders *b* and *d* are ground-rubber cylinders. The middle cylinder *c* is of felt, and the first cylinder *b* moistens the under side of the paper with the substance. The middle cylinder *c* spreads the necessary quantity of the substance, while the cylinder *d* distributes 10 equally the substance which has been spread by the felt-cylinder *c*, so that the spreading operation is effected in three phases.
- 15 By means of the device A lead and iron-salt solution, for instance, is spread, by means of the second device iron-salt solution is spread, and by means of the third device a platina solution, the salt solutions being of 20 secondary importance.
- From the drying device, arranged behind the last spreading device, the paper is led to a glazing apparatus and finally rolled or cut into sheets and is then ready for use.
- 25 I would state that all the troughs in each set of chemical-applying devices—that is to say, troughs *a a a* of the device through which the paper passes after leaving the paper-roll—contain the same chemical solution, as 30 lead-and-salt solution. The troughs *a' a' a'* of the second set of chemical-applying devices contain the same chemical solution—*i. e.*, iron-salt solution—while the troughs of the third set of chemical-applying devices contain the

same chemical solution—*i. e.*, platina solution. Thus it will be seen the troughs *a a a* each contain one solution, the troughs *a' a' a'* each contain another solution, and so on. A common trough could be substituted for the troughs *a*, into which the rolls *b c d* could dip, 40 and this could be done for the other troughs.

A trough is preferably used for each roll simply to avoid the use of too great a quantity of the solutions which would be necessitated where common troughs are used. 45

What I claim is—

The herein-described method of preparing platina paper for photographic purposes wherein the sensitive surface is composed of successively-applied layers of chemical substances which consists in first moistening the paper on one side only, then applying a chemical substance to the moistened side of the paper, spreading the said substance smoothly over the said side of the paper, then drying 55 the whole, and then applying the successive layers of chemical substances in substantially the same manner, the drying operation being performed after one layer has been applied and before the application of a succeeding 60 layer.

In testimony that I claim the foregoing as my invention I have signed my name in presence of two subscribing witnesses.

ANDREAS LURZ.
